UNITED STATES PATENT OFFICE.

GEORGE HAROLD DUNN, OF OAK PARK, ILLINOIS, ASSIGNOR TO AMERICAN CAN COMPANY, OF NEW YORK, N. Y., A CORPORATION OF NEW JERSEY.

DISPENSER FOR PAPER TOWELS.

1,413,656.

Specification of Letters Patent. Patented Apr. 25, 1922.

Application filed January 30, 1917. Serial No. 145,554.

To all whom it may concern:

Be it known that I, GEORGE HAROLD DUNN, a citizen of the United States, residing in Oak Park, in the county of Cook and State of Illinois, have invented a new and useful Improvement in Dispensers for Paper Towels, of which the following is a specification.

This invention relates in general to dispensers for interfolded sheets and has more 10 particular reference to dispensers for paper towels designed for the dispensing of said towels singly.

Prior to my invention I am aware that it has been the custom to provide a box in 15 which the towels interfolded successively may be locked, the lowermost towel of a pile contained therein having an edge or end disposed through a slot provided for the purpose in the bottom of the box. Since 20 these towels are designed for toilet purposes, the hands of persons withdrawing them are usually wet and unless the towels come easily through the slot tearing results from the combined dampness and pull, requiring the 25 frequent attention of attendants. Effort has been made to overcome this by placing rollers at the edges of the slot and by rounding the surfaces at its point, but this has not been entirely successful. I have discovered that 30 the chief frictional resistance to the withdrawal of the interfolded sheets occurs where the fold in the sheet must be straightened out as the sheet slides through the slot. The folds in piles of sheets of this character are 35 located along the side edges of the box and when the end depending through the slot is pulled the fold is first bent downwardly pressing, in the structures provided prior to my invention, with considerable force upon 40 the bottom of the box.

My present invention has for a principal object the provision of a structure which will permit the folds to straighten out without this incidental frictional resistance and has 45 for a purpose also the provision of a structure facilitating generally the removal of towels through a reduction of the friction resisting this removal.

A further object of the invention is the 50 provision of a dispenser for sheets of this character which may be cheaply manufactured and the parts of which will be so constructed and arranged as to be durable and not likely to require repair.

55 Other objects and advantages of the in-

vention will be apparent as it is better understood from the following description when considered in connection with the accompanying drawing illustrating a preferred embodiment thereof.

60

On the drawing,

Figure 1 is a partial perspective view of a box embodying my present invention;

Fig. 2 is a transverse sectional view 65 thereof;

Fig. 3 is an end elevation of a pile of interfolded sheets placed on the drawing to show the method of interfold usually adopted; and

Fig. 4 is an enlarged detail disclosing the 70 manner in which a box embodying my present invention permits the fold of the sheets to straighten out without great frictional resistance.

For the purpose of illustrating my invention I have shown on the drawing a box 5 which except for certain improvements may be of any preferred form and construction and which except as to these improvements 75 will not require particular description.

This box is, however, adapted to contain a pile of interfolded sheets or towels of the character shown in Fig. 3. Viewing this figure it will be noted that the bottommost towel has an end 6 coming from a relatively 80 sharp fold 7 extending along one side of the pile. A similar end 8 of the towel next above rests upon the end 6 and extends almost to the fold 7. From the fold 7 the towel having the end 6 extends to the opposite side of the pile where it is given a fold 9 placing a short end 10 back upon the body of the towel. The pile of towels thus assembled and constructed is placed within the box with the end 6 fed through a slot 11 85 disposed longitudinally and preferably centrally of its bottom 12. The end 6 is adapted to be pulled to remove the lowermost towel and in this operation pulls down the end 8 of the towel next above it, leaving the 90 end 8 in the position previously occupied by the end 6.

In a dispenser embodying my invention I provide a pair of supports 13 for the stack of towels, each of these supports consisting 105 of a metal sheet having side flanges 14 secured upon the bottom 12 and having the central or body part 15 curved upwardly as shown on the drawing. This arrangement permits the fold 7, as shown in Fig. 4, to 110

- first bend downwardly when the end 6 is pulled and to straighten out before passing the support. This straightening of the fold is indicated in dotted lines in the figure.
- 5 The upper or outer surface of the supports 13 is of bright material and is not lithographed or coated with varnish, paint, or other covering as is the remainder of the box in accordance with the usual practice.
- 10 Prior to my invention it has been the custom to lithograph the bottom as well as the remainder and this has resulted in the interposition of considerable friction to the withdrawing of the towels. It is to be re-
- 15 membered in this connection that towels of this character are unsized and are of rough absorbent material and any appreciable friction causes them to tear rather than slide from the dispenser.
- 20 It is thought that the invention and many of its attendant advantages will be understood from the foregoing description, and it will be apparent that various changes may be made in the form, construction and
- 25 arrangement of the parts without departing from the spirit and scope of the invention of sacrificing any of its material advantages, the form hereinbefore described being merely a preferred embodiment
- 30 thereof.

I claim:

1. A dispenser for folded sheets of paper and the like which are superposed one on the other in a gravitating pile with their
- 35 folds arranged at the opposite sides of such pile, comprising an enclosing receptacle

provided with a longitudinal central slot in the bottom thereof, said bottom being also provided with elevated and rounded smooth longitudinal antifriction surfaces arranged 40 at the opposite sides of the slot and near the side walls of the receptacle and relatively remote from said slot, and supporting said pile and the lowermost folded sheet at two points close to the folds of the sheet, so as 45 to cause with certainty the folds of the sheet which is being withdrawn to straighten out smoothly without disarranging the sheet next above.

2. A dispenser for folded sheets of paper 50 and the like which are superposed one on the other in a gravitating pile with their folds arranged at the opposite sides of such pile, comprising an enclosing receptacle provided with a longitudinal central slot in 55 the bottom thereof, said bottom being also provided with rounded antifriction surfaces of smooth shiny metal elevated above said bottom and arranged at the opposite sides of the slot, and supporting said pile 60 and the lowermost folded sheet at each side of the slot so as to cause with certainty the folds of the sheet which is being withdrawn to straighten out smoothly under a relatively light pull without disarranging the 65 sheet next above.

Signed in the presence of two subscribing witnesses.

GEORGE HAROLD DUNN.
